US00D693481S

(12) **United States Design Patent**
Johnson et al.

(10) **Patent No.:** **US D693,481 S**
(45) **Date of Patent:** **** Nov. 12, 2013**

(54) **MOLDED SURFACE OF A CONCRETE PRODUCT**

1,086,975 A 2/1914 Aaronson
1,166,312 A 12/1915 Barten

1,751,272 A 3/1930 Forman
1,776,999 A 9/1930 Jensen
1,982,730 A 12/1934 Erkman

(71) Applicant: **Anchor Wall Systems, Inc.,**
Minnetonka, MN (US)

(72) Inventors: **Jay J. Johnson**, Star Prairie, WI (US);
Robert Joel Wolter, Chaska, MN (US);
Robert Brian Burnquist, Chaska, MN
(US); **Steven Paul Bennett**, Coon
Rapids, MN (US)

(73) Assignee: **Anchor Wall Systems, Inc.,**
Minnetonka, MN (US)

(**) Term: **14 Years**

(21) Appl. No.: **29/421,985**

(22) Filed: **Nov. 5, 2012**

(51) LOC (9) Cl. **25-01**

(52) U.S. Cl.

USPC **D25/113**

(57) **CLAIM**

The ornamental design for molded surface of a concrete product, as shown and described.

DESCRIPTION

FIG. 1 is a front perspective view of a molded surface of a concrete product according to our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

1 Claim, 8 Drawing Sheets
